TERMINAL CLAMP

Filed Dec. 7, 1927

Inventor
L.A. WALLIS,

By

A. P. Greeley

Attorney

UNITED STATES PATENT OFFICE

LONNIE A. WALLIS, OF JOPLIN, MISSOURI

TERMINAL CLAMP

Application filed December 7, 1927. Serial No. 238,360.

My invention relates to terminal clamps, particularly adapted to connect the post of a storage or other battery with the motor or lighting circuit or other devices in which current is to be made use of and my invention has for its object to provide a device for this purpose which will be simple, strong and inexpensive to construct and will be adapted to be quickly and firmly secured in place and readily detached.

With these and other objects hereinafter described in view my invention consists in the construction and combination of elements hereinafter described and claimed.

15 Referring to the drawings:

Figure 1 is a perspective view of a battery terminal embodying my invention in closed position.

20 Figure 2 is a perspective view of the same showing the parts separated.

Figure 3 is a perspective view of the socket carrying members, and

Figure 4 is a top plan view of the battery terminal in position.

25 In the drawings 1 indicates the socket carrying member of my battery terminal and 2 indicates the clamping member. The socket carrying member 1 is formed of a single piece of brass or other metal and has at 3 a hollow

30 socket adapted to receive a cable or wire 4 leading to the motor, lighting system or other device in which the current from the battery is to be used. In the body of the socket carrying member, at right angles to the socket

35 is formed a recess 5 extending from its upper to its lower face adapted to bear against the post 6 of the battery and leading from this recess 5 is an arc shaped recess 7 terminating in a shoulder 8 which extends horizontally

40 towards the battery post 6 and extends vertically from the upper to the lower face of the socket carrying member.

The clamping member 2 is formed with a

45 recess 9 adapted to fit the battery post 6 and has at its inner end a head 10 having its outer surface curved to loosely fit the recess 7 of the socket carrying member and having a projecting shoulder 11 adapted to fit against and engage the shoulder 8 of the socket carrying member 1. The head 10 with its shoulder 11

is continuous from the upper to the lower face of the member and as the recess 7 is also continuous from the upper to the lower face of the socket carrying member the head 10 may be inserted into recess 7 by sliding it in from above or below or may be inserted laterally.

The free or outer ends 12 and 13 of the socket carrying member and clamping member may be drawn and held in clamping position by any convenient means, the means shown consisting of a headed bolt 14 extending through openings 16 and 17 in the ends 12 and 13 respectively and held in clamping position by nut 15.

By forming the recess 7 and the head 10 each continuous from upper to lower face of the member in which it is found the manufacture of these members is facilitated as very little machining is needed to finish these parts.

Having thus described my invention, what I claim is:

1. A battery terminal comprising two members adapted to enclose between them a battery post, one of said members having a wire receiving socket open at both ends and being provided at one side of the wire running socket with an arc shaped recess extending from its upper to its lower face and terminating in a retaining shoulder extending towards the battery post, and the other member having at one end a head adapted to fit the arc shaped recess of the other member and terminating in a shoulder adapted to engage the retaining shoulder thereof the head being movable into and out of the arc shaped recess by a sliding movement and in a direction parallel with the battery post, and means for drawing the free ends of said members together.

2. A battery terminal clamp comprising a socket carrying member and a clamping member adapted to clamp between them a battery post, the socket carrying member having a recess terminating in a retaining shoulder, the recess and shoulder extending from the upper to the lower face of the socket carrying member and a clamping member having at its inner end a head adapted to fit the recess in the socket carrying member terminating in

a shoulder adapted to engage the retaining shoulder of the socket carrying member the head being movable into and out of the arc shaped recess by a sliding movement in a direction parallel with the battery post and means for holding the free ends of the members in clamping position.

In testimony whereof, I hereunto affix my signature.

10
